UNITED STATES PATENT OFFICE.

EDWIN BLUTHARDT, OF CHICAGO, ILLINOIS.

BOTTLE SEAL AND CAP.

1,131,201.

Specification of Letters Patent.

Patented Mar. 9, 1915.

Application filed March 5, 1913. Serial No. 752,193.

To all whom it may concern:

Be it known that I, EDWIN BLUTHARDT, a citizen of the United States of America, and a resident of Chicago, county of Cook, and 5 State of Illinois, have invented certain new and useful Improvements in Bottle Seals and Caps, of which the following is a specification.

This invention relates to caps and seals 10 for bottles or other containers.

The main objects of the invention are to provide a cap and seal of this class designed to indicate that the original contents of the 15 containers to which they are attached are still in the containers when the cap is intact; and to provide means for indicating whether bottles have been fraudulently reused with imitated caps after the original contents of 20 the bottles are removed. The cap is preferably knitted and may completely or partially inclose the container, the end or ends of the strand or strands of which the cap is formed being arranged to facilitate unraveling of the cap for the purpose of removing the same.

Other objects of the invention are to provide a frame or ring in combination with a knitted cap whereby, while the caps are formed independently of the containers with 30 which they are associated, they may be combined therewith, to the same practical purposes, as if actually woven around the containers; and to provide in combination with such cap and band, seals or other suitable 35 fastening devices for the band and the free end or ends of the material forming the cap.

An illustrative embodiment of this invention is shown in the accompanying drawings, in which:

Figure 1 is a perspective view of a bottle provided with a woven cap and a suitable seal. Fig. 2 is a fragmentary sectional perspective view of the bottle showing the fastening devices for the cap but omitting the cap itself. Fig. 3 is a detail showing an example of stitch by which the bottle cap may be formed, and also illustrating how a tack may be used to secure the same against 45 being accidentally unraveled. Fig. 4 is a plan in detail of a metallic band and seal employed to secure caps to bottles.

The present invention is designed to safeguard merchandise of known quality against 5 the substitution therefor by dealers or dis- pensers of merchandise of inferior or un-

known quality, and to attain this end the invention provides a novel and distinctive cap or seal for inclosing the containers of merchandise. This cap or seal consists preferably of an openly knitted fabric or cord so 60 interlooped upon itself that it is capable of being unraveled. The cap is applied, for example on a bottle as shown in the drawings, to cover the bottle closure so that the fabric may be removed and unraveled by 65 pulling the end of the cord or strand forming the cap. The invention thus provides a seal or cap of distinguishing characteristics and, when removed in the presence of customers in the regular intended way by 70 unraveling, affords such a noticeable operation as not to admit of deception.

In the precise arrangement shown in the drawings a bottle 1 having a flange 2 at its mouth, and a reduced neck 3, is provided 75 with a closure such as a cork 4. A knitted cap 5 is fitted over the mouth of the bottle and at its edge is contracted snugly into the neck part 3 of the bottle by a band 6 having its ends secured together by a seal 7. The 80 cap 5 is shown formed of a single cord having one end secured, as to the band 6 or the seal 7, and its opposite end passes through a hole 8 in the thumb tack or seal 9 secured to the bottle closure 4.

The band 6 serves as a form on which the cap 5 may be knitted. The stitch employed is preferably a chain stitch or other similar one which will admit of unraveling the cap by pulling the knotted end 10 of the cord. 90 The caps are formed around the bands 6, while the latter have their ends free or loosely held together by leaden seals 7 as indicated in Fig. 4. After the cap is placed on the bottle the band 6 is tightened as indicated by full lines in Fig. 4 and the seal is clamped in place.

In operation to remove the bottle closure the thumb tack 9 is first removed and serves as a grip for the purpose of pulling the cord 100 outwardly and thereby unraveling the cap 5. The cap in this manner is obviously completely destroyed while the band 6 or seal 7 need not be broken. Accordingly if empty bottles with the woven caps removed still 105 have the original bands and seals intact, the latter remain as evidence tending to show that the bottles have not been fraudulently employed with imitated caps after the original contents are removed, as it would be ex- 110

tremely difficult if not impossible to weave a new cap around one of the bands when in place on the neck of a bottle.

Although but one specific embodiment of this invention has been herein shown and described, it will be understood that numerous details of the construction shown may be altered or omitted without departing from the spirit of this invention as defined by the following claims.

I claim:

1. The combination with a container having a closure, of a cap covering said closure comprising a cord so interlooped upon itself that the cord may be unraveled and the cap removed by pulling one end of the cord, and means for normally preventing the unraveling of said cap.
2. A bottle cap made of an openly knitted fabric capable of being unraveled and suitably formed to contain the head of a bottle, and a fastening device for preventing the unraveling of said fabric.

Copies of this patent may be obtained for five cents each, by addressing the "Commissioner of Patents, Washington, D. C."

3. The combination with a bottle having a closure and a reduced part below its mouth, and a cap extending over said closure and fitting into said reduced part, said cap comprising a cord so looped upon itself that the cord may be unraveled and thereby uncover the closure, and means normally preventing the unraveling of said cap.

4. A container having a closure, means for sealing said closure comprising a cap secured in position over said closure and including a cord secured to the remainder of the cap, suitably woven that it may be unraveled and the cap removed by pulling the cord, and a device for securing one end of said cord to the bottle closure.

Signed at Chicago this 21st day of February, 1913.

EDWIN BLUTHARDT.
